UNITED STATES PATENT OFFICE.

FRANK BRABSON, OF NEWARK, NEW JERSEY, ASSIGNOR TO GREENE, TWEED & CO.,
A CORPORATION OF NEW YORK.

DOOR LOCK.

Application filed September 8, 1923. Serial No. 661,580.

To all whom it may concern:

Be it known that I, FRANK BRABSON, a citizen of the United States, and a resident of Newark, in the county of Essex and State 5 of New Jersey, have invented certain new and useful Improvements in Door Locks, of which the following is a specification.

This invention relates in general to door locks of the type comprising two longitudinally aligned bolts or locking rods secured to a door or the like to cooperate with keepers on the door frame, and means including a knob or handle arranged between said bolts for simultaneously moving said 10 bolts longitudinally in opposite directions to engage with or disengage from said keepers to lock or unlock the door. The bolts of such locks are several feet long and extend the full length of a door or swinging window, and much difficulty is usually encountered in applying known locks of this character to a door due to the fact that the bolts must be first secured to the operating mechanism or knob and the whole lock as an 15 entity secured to the door. Two men are usually required for this purpose, one to steady and position the device while the other fastens the same in position.

The primary object of my invention is to 20 provide a locking mechanism of the character described embodying novel and improved features of construction whereby the mechanism can be easily assembled, located on and secured to a door piece by piece by 25 one man.

Another object is to provide such a locking mechanism embodying novel and improved operating mechanism for the bolts which can be easily and quickly positioned 30 and secured on a door and connected to the bolts.

Further objects are to provide a locking mechanism of this character in which the bolts can be fully actuated in both directions by rotations of the operating knob or handle through an angle of substantially 90 degrees in opposite directions; to provide an improved bearing for the knob or handle to ensure smooth and easy rotation thereof, and to obtain other results and advantages as may be brought out by the following description.

Referring to the accompanying drawings, in which like numerals of reference design-

nate the same parts throughout the several 55 views,

Figure 1 is a front elevation of a door locking mechanism embodying my invention showing the same applied to a door;

Figure 2 is an enlarged front elevation of 60 the operating mechanism;

Figure 3 is a transverse vertical sectional view through the door locking mechanism, portions being broken away;

Figure 4 is a vertical longitudinal sectional view taken on the line 4—4 of Figure 3;

Figure 5 is a horizontal sectional view taken on the line 5—5 of Figure 3;

Figure 6 is a rear elevation of the upper 70 section of the operating mechanism casing;

Figure 7 is a detached perspective view of the base section of the operating mechanism casing;

Figure 8 is a front elevation of the base 75 of the casing showing the same applied to a door;

Figure 9 is a similar view showing the manner of assembling the locking bolts in 80 the base section of the casing;

Figure 10 is a perspective view of the actuating end of one of the locking bolts;

Figure 11 is a top plan view of one of the keepers on the frame of a door to cooperate 85 with one of the locking bolts, and

Figure 12 is a vertical longitudinal sectional view through a part of the door frame and the keeper.

In the specific embodiment of the invention shown on the drawings, the reference 90 character A designates the operating mechanism of the door lock embodying the invention which cooperates with locking bolts or rods B arranged in substantially longitudinal alignment to slide longitudinally of the door in guides C, said bolts cooperating with keepers D secured in the frame of the door. When the bolts B are in engagement with the keepers D the door is locked, and when the bolts are moved longitudinally by the operating mechanism A out of engagement with the keepers D the door is unlocked.

The operating mechanism includes a base section 1 preferably formed of sheet metal and having substantially centrally of its 100 length oppositely disposed upturned flanges

2. The ends of the base section are provided with prongs or points 3 which may be con-

veniently stamped from the metal of the base, and substantially centrally of its length the base is provided with an opening 4 to form a bearing for an operating knob or handle 5. The operating handle or knob 5 includes a handle portion 6 and a shank portion 7 which is rotatably mounted in an upper casing section 8 to cooperate with the base section 1 to form a housing for the 10 operating mechanism. The inner end of the shank 7 has rigidly secured thereto a pinion 9 to cooperate with racks 10 one formed at one end of each of the locking bolts B.

The locking bolts B are preferably formed 15 of substantially half round metal and the rack 10 of each of the rods is laterally offset in a direction opposite to that of the rack of the other rod, as clearly indicated in Figures 4, 9 and 10. The said racks may be 20 cast integral with the rods B or formed separately and rigidly secured thereto as by riveting. The inner ends of the racks are formed with shoulders 11 for a purpose hereinafter described. The outer ends of the 25 bolts B are formed with transverse openings 12 which are preferably located on the bolts at the position where the guides C engage the bolts. The guides C for the rods are preferably tubular in construction so as 30 to slidably receive the rods and guide them in their longitudinal movement on the door.

In assembling and applying the lock to a door, a shallow recess 13 is formed in the door at the position where it is desired to 35 place the operating mechanism A. The base section 1 is then applied to the door with the opening 4 substantially registering with the recess 13 and the flanges 2 projecting outwardly from the door and extending longitudinally thereof. The ends of the base section are then tapped as with a hammer to 40 embed the prongs 3 in the door, the said prongs then holding the base section in position. The bolts B are then separately applied to the door with the outer end of one 45 rack abutting the shoulder 14 formed at the adjacent end of the other rod and with the inner ends of the racks positioned substantially equidistantly from the center of the 50 opening 4 at opposite sides thereof. The racks are also in engagement with the corresponding flange 2 of the base section, and the bolts may be held in this position by driving nails or the like 15 through the 55 openings 12 into the door. In Figure 9 of the drawings the uppermost bolt is shown in its adjusted position, while the lowermost bolt is shown as being applied to the door.

Figure 4 of the drawings shows both bolts 60 in their adjusted relative positions. When the bolts and racks 10 have been thus arranged, the upper section 8 of the housing with the handle 5 and pinion 9 applied thereto is slipped over the flanges 2 of the 65 base section 1, with the pinion 9 meshing

with the two racks 10, as clearly shown in Figures 3 and 4. The inner end of the pinion is preferably formed with a rabbeted portion 16 to fit the opening 4 in the base section to form a bearing for the inner end 70 of the shank 7 of the handle. With this construction it will be observed that the said shank 7 is provided with bearings at both ends so as to prevent tilting of the pinion 9 during operation and to ensure smooth and 75 unbinding action of the pinion with the racks 10. Preferably the pinion 9 is conical to facilitate its insertion between the racks 10. After the upper section 8 of the housing has been thus positioned, it is secured to the door by means of screws or the like 17. The upper section 8 snugly fits over the sides of the base section 1 so as to hold the latter 80 securely against movement. The guides C may be slipped on the bolts B before they are placed on the door or after the housing 8 has been secured in place, as may be desired, and after the housing has been positioned the guides are moved to their proper 85 locations and fastened to the door by screws or the like 18.

With this construction it will be observed that rotation of the handle 5 will through the pinion 9 and racks 10 cause longitudinal movement of the bolts B in opposite directions, movement of the handle in one direction sliding the bolts into engagement with the keepers D while movement of the handle in the other direction disengages the bolts from the said keepers to unlock the door. A 100 rotation of the handle through substantially an angle of 90 degrees is sufficient to operate the bolts into either their locking or unlocking position. Inward movement of the bolts, that is movement to their unlocking positions, is limited by engagement of the outer end of each of the racks 10 with the shoulder 14 of the other rod. Movement of the bolts in the other direction is shown as 105 limited by engagement of the shoulder 11 at the inner ends of the racks with the screws 17, but it will be understood that other stop means than the screws 17 may be utilized.

It will thus be understood that the lock embodying my invention can be easily and 110 quickly assembled and applied to a door piece by piece by one man. The base section 1 serves both as an index of the position at which the operating mechanism should be placed, and as a guide for the 115 rack bars 10, as well as an additional bearing for the handle 5.

While I have shown and described the locking mechanism as embodying certain 120 details of construction, it will be understood that this is mainly for the purpose of illustrating the principles of the invention and that many modifications and changes 125 can be made in the details of construction 130 without departing from the spirit or scope

of the invention. Therefore, I do not desire to be understood as limiting myself except as required by the following claims when construed in the light of the prior art.

5 Having thus described the invention, what I claim is:

1. A door lock including a longitudinally movable bolt, an operating mechanism for actuating said bolt, a housing for said mechanism including a base section formed of sheet metal and having prongs stamped therefrom to position the section on a door, and a top section adapted to telescope over said base section to enclose said operating mechanism.

2. A door lock including a longitudinally movable bolt having a rack at one end thereof, an operating mechanism housing including a base section formed of sheet metal having prongs stamped therefrom to initially position the section on a door to underlie said bolt, a top section adapted to telescope over said base section, an operating handle journaled in said top section, a pinion on said handle to engage said rack to operate said bolt, and means for securing said top section to the door.

3. A door lock including two longitudinally aligned and movable bolts each having a rack at the end adjacent the other bolt, each of said bolts having a shoulder adjacent the inner end of its rack to engage the outer end of the other rack to limit movement of said bolts toward each other, an operating mechanism housing including a base section adapted to be initially applied to a door to indicate the proper position of said racks, said base section being formed with an opening, a top section to telescope over said base section, an operating handle journaled intermediate its ends in said top section, a pinion on said handle to engage said racks to operate said bolts, and means for securing said top section to the door with the pinion end of said handle engaging said opening in the base section to form a second bearing for said handle.

4. A door lock including a longitudinally movable bolt formed to be engaged by and cooperate with an operating mechanism for moving the bolt after the bolt has been initially applied to a door, an operating mechanism for the bolt constructed to be applied to a door after said bolt is positioned thereon to engage and cooperate with said bolt to move the latter, a housing for said operating mechanism including a base section adapted to be applied to the door and underlie said bolt, a top section in which said operating mechanism is mounted adapted to telescope over said base section, said base section serving to lo-

cate and guide said top section to cause proper engagement of said operating mechanism with said bolt, and means for securing said top section to the door.

5. A door lock including a longitudinally movable bolt, an operating mechanism for actuating said bolt, a housing for said mechanism including a base section formed with means to initially position the same on a door, a top section adapted to snugly fit over said base section, and means for positively securing said top section to the door whereby said base section may be positioned on a door independently of said top section and said top section positively secure said base section to the door.

6. A door lock including a longitudinally movable bolt having a rack at one end thereof, an operating mechanism housing including a base section formed with means to initially position the same on a door to underlie said bolt, said base section having an opening therein, a top section adapted to snugly telescope over said base section, an operating handle journaled intermediate its ends in said top section and having an end portion to fit said opening in the base section as said top section is applied over said base section, a pinion on said handle to engage said rack to operate the bolt, and means for positively securing said top section to the door, whereby said base section may be positioned on the door independently of said top section and guide said top section to cause proper engagement of said pinion with said rack and said top section positively secures said base section against movement on the door.

7. A door lock including two longitudinally aligned and movable bolts each having a rack at the end adjacent the other bolt, an operating mechanism housing including a sheet metal base section adapted to be initially applied to a door and having opposite longitudinal upstanding flanges to indicate the proper location of and guide said racks, a top section adapted to snugly telescope over said base section, an operating handle journaled in said top section, a pinion on said handle to engage both said racks for operating said bolts, said flanges guiding said top section to cause proper engagement of said pinion with said rack, and means for securing said top section to the door, whereby said base section may be initially applied to a door independently of said top section to serve as a guide in assembling the lock and said top section positively secure said base section to the door.

FRANK BRABSON.
